UNITED STATES PATENT OFFICE

JOSEPH SUNNEN, OF KIRKWOOD, MISSOURI

HONING MACHINE FOR PISTON PIN HOLES

Application filed December 4, 1931. Serial No. 578,923.

My invention has relation to improvements in grinding machines adapted for use in refinishing small sized bores, such as wrist pin holes and similar small bearings common in 5 internal combustion engines. The machine is akin to a reamer, although it operates primarily by abrasive action rather than shearing action, and it consists in the novel features of construction more fully set forth in 10 the specification and pointed out in the claims.

The invention is primarily for the purpose of reboring small holes to receive new pins, for which reason it is essential that the 15 tool holder be so designed as to employ great relative strength and rigidity comparative to the size thereof. It is, therefore, the object of the present invention to provide a pin hole grinder having an abrasive element rigidly carried on a rotatable spindle, or mandrel, that is adapted to traverse the hole being ground; one in which the spindle, although supported only at one end, possesses 20 the degree of rigidity essential to produce a true cylindrical hole, one in which the abrasive element is adjustably mounted in the mandrel in order to adapt the grinder to different sizes of pin holes so that one tool may 25 be made to perform the grinding operation on a wide range of holes; one which operates with a minimum amount of vibration; one in which fixed guide elements are provided to cooperate with the abrasive element and confine the rotation of the same to a substantially 30 fixed orbit for any adjustment, thereby insuring the production of a cylindrical hole; one embodying means for causing the grinding element to adhere to the surface being 35 ground without chattering; and one in which the guide elements of the tool are composed of a suitable metallic alloy so that they will have a relatively long life and will wear substantially uniformly throughout their entire 40 extent.

It is also an advantage to employ but a 45 single abrasive element and thus avoid excessive weakening of the mandrel by providing a plurality of grooves for receiving the abrasive elements. This feature is important on account of the small diameter of

the mandrel necessary to operate on pin holes of small diameter, such as wrist pin holes.

It is a further object of the invention to form the guide elements integrally with the tool holder, or mandrel, as a matter of simplicity and economy of manufacture, and at the same time constituting the holder of a material that will embody the requisite strength and rigidity essential to it, which material at the same time embodies properties essential to the satisfactory performance of the guide elements. I have discovered that one material, possessing the properties essential both to the guide elements and the tool holder, consists of a zinc alloy containing 60 both aluminum and copper. 65

Further objects of the invention are to provide a horizontally disposed revoluble member or mandrel having a longitudinally disposed groove formed therein and provided with a plurality of longitudinally disposed radially projecting ribs arranged in spaced peripheral relation with said groove, there being an adjustable blade longitudinally disposed in said groove having an obliquely disposed portion, and a mount or shoe movably disposed in said groove and engaging said oblique portion and carrying on its outer face an abrasive stick whereby the adjusting longitudinal movement of said blade causes radial movement of said abrasive stick, said longitudinal ribs forming non-abrasive points of engagement with the cylinder surface operated upon and serving to steady said revoluble member during the operation 85 thereof. 80

Additional objects of the invention are to provide a bearing member adapted to be stationarily mounted, said bearing member having a horizontally disposed bearing in which is journaled a revoluble member or mandrel provided with cylinder engaging elements, said member being provided with bearings spaced from the first bearing and having journaled therein a rock shaft carrying an 95 electric portable drill which is engageable with the revoluble member so as to actuate the latter, said rock shaft being operable to bring said drill into and out of operative engagement with said revoluble member. 100

With these and other objects in view, my invention consists in certain novel features of construction and arrangement of parts, hereinafter more fully described and claimed, 5 and illustrated in the accompanying drawings, in which—

Figure 1 is a top plan view of my piston pin hole grinding machine, showing the driving means engaged with the mandrel or tool 10 holder.

Figure 2 is a vertical cross section taken on line 2—2 of Figure 1.

Figure 3 is a vertical cross section taken on line 3—3 of Figure 1, showing the driving 15 means in disengaged position.

Figure 4 is a longitudinal cross section taken on line 4—4 of Figure 1.

Figure 5 is an enlarged vertical cross section taken on line 5—5 of Figure 4.

20 Figure 6 is a vertical cross section taken on line 6—6 of Figure 4.

Figure 7 is a vertical cross section taken on line 7—7 of Figure 4.

Figure 8 is a vertical longitudinal section 25 taken on line 8—8 of Figure 4.

Figure 9 is a vertical cross section taken on line 9—9 of Figure 2.

Figure 10 is a vertical cross section taken on line 10—10 of Figure 1.

30 Figure 11 is a vertical cross section taken on line 11—11 of Figure 10.

Referring by numerals to the accompanying drawings, 10 indicates a bench on which rests a base 11. The upper end of which is 35 provided with a horizontally disposed wall 12 having a central aperture 14. A bearing member or casting 15 is provided with a downwardly presented tubular extension 16 which rests on wall 12. A bolt 17 extends 40 through the apertured top wall of member 15 and through the aperture 14 and has its lower end engaging said bench or support 10 while the upper end 17a of said bolt is screw-threaded and receives a nut 17b where- 45 by said casting or member 15 can be clamped securely in position on the base 11.

Casting 15 is disposed substantially in the horizontal plane above said base 11, and terminates at its forward end in a horizontally disposed tubular member 18 which forms a journal for a mandrel structure 19, hereinafter more fully described. The other end, which is preferably disposed slightly below the horizontal plane of member 18, terminates in a pair of spaced coaxial lugs 20, 20 in which is journaled a rock shaft 21. This shaft is preferably rectangular in cross section and has the lower end 22 of a bearing member 24, mounted on it between lugs 20.

50 The upper end 25 of this bearing member forms a journal for a driver spindle 26, the outer end of which is reduced, and has mounted thereon a driver disk 27. This driver disk, which may be of any desired construction, is 55 preferably formed with a peripheral groove

which is adapted frictionally to engage a driven disk 28 mounted on the mandrel structure 19 adjacent to the corresponding end of member 18.

Normally bearing member 24 occupies a 70 position shown in Figure 3 wherein the driver disk 27 is disengaged from the driven disk 28. The bearing member 24 has a downwardly projecting lug 29 formed integral with it, in which one end of a rod 30 is secured. The other end of this rod terminates past the front edge of bench 10 and is pivotally connected at 31 to a treadle 32. By pressing on said treadle, journal member 24 is rocked forwardly to bring the driver disk 27 into operative engagement with the driven disk 28, as shown in Figure 2. When the pressure is removed, journal member 24 moves to its normal or disengaged position shown in Figure 3, under the influence of a 75 coiled spring 34.

The driver spindle 26 is provided at one end with a head 35 having an axial bore 35a and a diametrically disposed slot 35b. A driver shank 36 is adapted to be secured in a chuck 37 of an electric hand drill 38 and has its outer end formed with an enlargement 36a which fits into said bore 35a. This enlargement is provided with a diametrically disposed pin 39, the ends of which are adapted to enter the slots 35b, thereby establishing driving connection between the drill and the driver spindle 26. The enlargement 36a is slightly tapered toward both ends to permit loose fit thereof in said bore 35a and the pin 39 has a loose fit in said slot 35b. This arrangement allows driving engagement of the drill with the driver's spindle 26 without requiring said drill to be in perfect axial alignment therewith.

The drill 38 is supported in position by a socket 40 which latter is slidably mounted on the projecting end of rock shaft 21. The socket is vertically disposed to one side of said bar (see Figs 10 and 11) and receives the usual tubular portions or handle 38, which extends diametrically from said drill so that said drill rests on the upper end of said socket. This socket is formed with an extension 40a which is arranged to one side 100 of said socket and is provided with a horizontally disposed hole 41 in which the bar 21 is received. Preferably this hole is formed tapered at one end, as shown in Figure 11, so that said drill can adjust itself and is not 105 rigidly held in position.

Thus when the journal member 24 is rocked, bar 21 is rocked therewith, thereby causing drill 38 to move substantially in coaxial alignment with the driver spindle 26. This arrangement permits easy attachment and detachment of the drill as by shifting the socket member 40 away from the journal bearing 24 drill 38 and the driver shank 36 are moved away from driver spindle 26, 110 115 120 125 130

thereby permitting said drill to be moved from socket member 40. To bring the drill into engagement with the machine, the drill is placed in position in socket member 40 and the latter is then moved forwardly against the machine so as to bring the enlargement 36a into engagement with the head 35.

The mandrel structure 19 supports a mandrel 42 revolvably in the journal 18. This structure comprises a driven spindle 44 journaled in bearing 18 and having its ends extending past the ends of the latter. One of said ends is reduced in diameter as indicated at 44a and is screw-threaded to receive a hub 28a of driven disk 28. A short shaft 45 extends through the reduced end 44a. The inner end of said shaft is provided with a head 46 which is loosely held in a seat 47 formed in spindle 44 for this purpose. The projecting portion of said shaft is tapered, as indicated at 48, to receive the tapered bore of a knurled adjusting member or knob 49. The end of the shaft is threaded and receives a nut 50 by means of which knob 49 is held in position.

The opposite end of driven spindle 44 is formed with a tubular head 51 which is provided with an external screw-thread for receiving a coupling 52. This coupling has a radial flange 52a which bears against head 42a of mandrel 42 and thus holds the latter securely in position against the threaded externally screw-threaded head 51 of the driven spindle 44 and in axial alignment therewith.

In order to eliminate driving stresses from the coupling and the coupling members 52 and 42a and in order to insure efficient driving connection between the tubular spindle 44 and mandrel 42, the head 42a of the latter is provided with an outwardly presented longitudinally disposed lug 55 which fits into a longitudinally disposed groove 56 formed in the tubular head or enlargement 51.

The mandrel 42 is of a comparatively small diameter so as to fit small-sized bores. This mandrel is provided with a longitudinal groove 57 which is closed near the outer end thereof, as indicated at 58. Said groove extends through said mandrel and through the head 42a and opens into said tubular spindle 44. A cylinder engaging element or hone shoe 58', having an abrasive element 59, is mounted in this slot and projects radially therefrom. Mandrel 42 is provided with a pair of longitudinally disposed ribs or non-abrasive elements 60 which are preferably formed integral therewith and extend therefrom at points spaced peripherally from said element 59. These ribs are substantially co-extensive with said element, as shown in Figure 4. They are formed with curved faces 61 which engage the surface of the bore. Thus the inner surface of a cylinder or bore 65 is engaged by an abrasive element at one

point only and is engaged by non-abrasive elements at two points spaced from each other and from the abrasive element. These non-abrasive elements or ribs 60 serve to maintain the mandrel 42 in proper alignment in the bore and to steady the tool so as to prevent chattering or binding thereof when in use.

The abrasive element 59 is secured in any suitable manner in shoe 58' and the latter is of sufficient depth so as to have ample bearing surface with the sides of the groove 57. One side of shoe 58' is cut away, as indicated at 58a, so as to accommodate a wedge 62 which is slidably arranged in said groove to one side thereof. The top wall of the cut-away portion is disposed obliquely relatively to the longitudinal axis of the mandrel and the top 62a of the blade is correspondingly inclined.

Blade 62 is movably arranged in groove 57 and is pivotally connected to an adjusting member 64, as indicated at 65. This adjusting member extends inwardly through the end 42a of mandrel 42 into tubular spindle 44 and has its inner end terminating in a boss 66 which is provided with a screw-threaded opening 67. Engaging this opening is an adjusting screw 68 disposed longitudinally in said driven spindle 44. This screw is provided with an enlargement 69 which fits into the recess 47 formed in head 46 of adjusting shaft 45. This enlargement is tapered toward each end to permit a slight angular movement of the adjusting screw relatively to said adjusting shaft.

A pin 70 extends diametrically through enlargement 69 and through head 46 and forms a universal joint therebetween. As shown in Figure 8, the ends of this pin are seated in head 46 and the medial portion of said pin is tapered to permit slight oblique movement of said adjusting screw relatively to said pin.

By turning knob or adjusting member 49 in the proper direction, shaft 45 and screw 68 are rotated so as to move adjusting member 64 outwardly toward the closed end 58 of groove 59. This causes outward movement of blade 62, which, through the interengagement of oblique faces of cut out portions 58a and 62a of the respective parts, moves cylinder engaging element 58' radially outwardly, thereby positioning the abrasive member 59 at a greater distance from the axis of rotation. When the knob 49 is turned in the opposite direction, adjusting member 64 and blade 62 are retracted, thereby permitting cylinder engaging element 58' to move radially inwardly. As the ribs 60 are formed integral with mandrel 42, they are not adjustable but they serve merely to space the element 58' in proper position within the bore.

A guard 71 is pivotally mounted at one end

between a pair of lugs 72, 72 which are formed integral with and extend upwardly from bearing 18, near the end adjacent to driving disk 28. Guard 71 extends rearwardly 5 alongside of said disk 28 and after passing said disk 28 it is offset or bent laterally and has its free end 74 terminating between the two spaced members forming driver disk 27. A bar 75 is secured to guard 71 immediately 10 in front of driver disk 27 and extends forwardly alongside the opposite side of driven disk 28. Guard 71 and bar 75 prevent an operator's hand and his clothing, or other objects, from being caught and drawn between 15 said disks.

Shoe 58 is preferably held in slot 57 by the tension of a spring 77 which is secured in said slot to one side of blade 62 and bears against one end of said shoe, the other end of the 20 latter being engaged by a shoulder 78 formed in said slot. Shoe 58' and abrasive stick 59 are adjustable radially of the mandrel to insure the desired finish of a bore.

In order to increase the range of usefulness 25 of the device, and enable it to be used in honing bores of varying diameters, mandrel 42 is formed detachable from the hollow spindle 44. A plurality of mandrels 42 of varying diameters is provided so that a mandrel of 30 proper size can be used. The attachment or removal of the mandrel can be quickly and easily made by the operation of coupling 52.

Supporting member 15 can be adjusted 35 about the vertical axis of bolt 17 so as to present the mandrel 42 at any angle desired. It can be readily attached to and detached from the bench. Member 36 provides an easily detachable and flexible connection between the drill 38 and the driver spindle 26. The 40 relative sizes of disks 27 and 28 can be varied to obtain the required speed of the mandrel.

When rock shaft 21 is rocked forwardly the spaced flanges of driver disk 27 engage 45 and grip therebetween the edge of driven disk 28 so that the mandrel 42 is positively driven by the drill 38 without the use of belts or other external transmission means.

When the driving mechanism, including 50 drill 38, bearing 24 and driver disk 27, occupies disengaged position (shown in Figure 3), it is desirable to limit the outward movement thereof. To this end, a pair of spaced vertical lugs 79 is formed integral with casting 15 adjacent to bearings 20. Similar pair 55 of lugs 80 is formed integral with bearing 22. Thus when member 24 is rocked away from member 15 lugs 79 engage lugs 80 and form a stop for member 24.

The mandrel 42 is preferably made of die 60 cast metal containing zinc, aluminum and copper of such proportions as will give the necessary strength and hardness in view of the fact that the lugs or guide elements 61, 61 are formed integrally with the mandrel 65 and must be non-abrasive when operating in

contact with the cylindrical wall of the hole being ground. In fact, one of the features of my invention is that but a single abrasive element 59 is used which makes it possible for the groove 57, in which the shoe 58' is 70 mounted, to be of substantial depth so as to give a wide latitude of radial adjustment to the shoe and, of course, abrasive element 59 carried thereby. In order that the rotation of the abrasive element 59 may be confined to 75 a definite orbit for grinding holes to a true cylindrical shape, there are two ribs 60 or guide elements spaced unequal distances radially from the abrasive element 59. The reason for the unequal spacing of the lugs 80 80 is to provide a means of correcting (in some instances) the tendency to grind a non-cylindrical hole. This correction may be accomplished by periodically reversing the 85 relative positions of grinder and thing being ground. It is obvious that the two guide lugs together with the abrasive element give three point contact within the hole that is being ground so that it is necessary to adjust but one 90 of these elements (preferably the grinding element 59) to maintain this three point contact for any size hole within the range of operation of the tool. This is axiomatic, as it is a fundamental law of mathematics that a circle can be described through any three 95 points not in a straight line. If the tool had more than three contact points it would be necessary to adjust more than one of the contacting points to adapt the tool to different sizes of cylindrical holes. If the tool had only two contacting points it would not rotate on a fixed circular orbit, but would have a tendency to "travel" or "creep" producing a hole that would not be truly cylindrical.

By making the mandrel 42 of die cast metal 100 having the proper composition so as to be of the correct degree of hardness with respect to the wall of the hole being ground the guide lugs 60, 60 may be cast integrally with the mandrel which greatly simplifies the construction of the mandrel. The composition of the alloy from which the mandrel is made must be such that it will be non-abrasive with respect to the metal defining the hole being ground and it must not possess ductility, such that it will spread or draw out away from the main body of the mandrel. On the other hand, the lugs 60, 60 should be sufficiently friable so as to gradually wear down by attrition smoothly and evenly.

I claim:

1. A honing machine comprising a stationary support, an electric hand drill detachably mounted on said support, a mandrel journaled in said support in spaced relation with said drill, said mandrel being provided with a longitudinally disposed groove and a plurality of longitudinally disposed ribs spaced peripherally from each other and from said groove, a longitudinally disposed blade mov-

ably mounted in said groove and having an obliquely disposed face, an abrasive stick carrying shoe disposed in said groove and in engagement with said oblique face whereby the longitudinal movement of said blade imparts radial movement to said shoe whereby the latter is adjustable radially relatively to the axis of rotation, said ribs forming non-abrasive surface engaging elements for 10 steadyng the tool, and a driving connection between said drill and said mandrel.

2. A honing machine comprising a stationary support, a mandrel journaled at one end thereof and provided with a longitudinally disposed groove and a pair of longitudinal ribs spaced peripherally from said groove, an abrasive stick shoe arranged in said groove, means associated with said mandrel for adjusting said shoe radially, a horizontally disposed rod loosely journaled in said support, a motor mounted on said rod, a driven member operatively associated with said mandrel, and a driver member associated with said motor and engageable with said 20 driven member for actuating said mandrel, said motor being oscillatable about the axis of said rod to bring said driver member into and out of operative engagement with said driven member.

3. A honing machine comprising a stationary support, a horizontally disposed mandrel journaled in said support and provided with a longitudinal groove and a plurality of longitudinally disposed ribs spaced peripherally from said groove, a blade movably arranged in said groove and adjustable longitudinally thereof, an abrasive stick shoe disposed in said groove and cooperatively arranged with said blade whereby the longitudinal movement of the latter imparts radial movement to said shoe, said ribs forming non-abrasive points of engagement with the surface of a bore operated upon by the abrasive stick of said shoe, thereby insuring proper alignment 40 of the article operated upon with said mandrel, a rock shaft mounted in said support in spaced relation with said revoluble member, a hand drill carried by said rock shaft and adjustable in a vertical and horizontal plane, a friction driver disk operatively associated with said drill, and a friction driven disk operatively associated with said mandrel and engageable by said driver disk, said drill and said driver disk being oscillatable on said 50 rock shaft so as to disengage said driver disk from said driven disk.

4. A honing machine comprising a stationary support adapted to be secured to a bench vise, a horizontally disposed mandrel journaled in said support and provided with a longitudinal groove and a plurality of longitudinally disposed ribs spaced peripherally from said groove, a blade movably arranged in said groove and adjustable longitudinally thereof, an abrasive stick shoe dis-

posed in said groove and cooperatively arranged with said blade whereby the longitudinal movement of the latter imparts radial movement to said shoe, said ribs forming non-abrasive points of engagement with the 70 surface of a bore operated upon by the abrasive stick of said mount, thereby insuring proper alignment of the article operated upon with said mandrel, a rock shaft mounted in said support in spaced relation with said mandrel, a hand drill carried by said rock shaft, a bearing member carried by said rock shaft, a driver spindle journaled in said bearing member, a friction driver disk fixed to said driver spindle, and a friction driven disk operatively associated with said mandrel and engageable by said driver disk, said drill and said bearing member being oscillatable on said rock shaft so as to disengage said driving disk from said driven disk.

5. A honing machine comprising a stationary support adapted to be secured to a bench vise, a horizontally disposed mandrel journaled in said support and provided with a longitudinal groove and a plurality of longitudinally disposed ribs spaced peripherally from said groove, a blade movably arranged in said groove and adjustable longitudinally thereof, an abrasive stick shoe disposed in said groove and cooperatively arranged with said blade whereby the longitudinal movement of the latter imparts radial movement to said shoe, said ribs forming non-abrasive points of engagement with the surface of a bore operated upon by the abrasive stick of said shoe, thereby insuring proper alignment of the article operated upon with said mandrel, a rock shaft mounted in said support in spaced relation with said mandrel, a hand drill carried by said rock shaft, a bearing member mounted on said rock shaft, a driver spindle journaled in said bearing member, a driver member fixed to said spindle, means for detachably connecting said spindle with said drill, a driven member operatively associated with said mandrel and engageable by said driver member, said rock shaft being oscillatable so as to disengage said driver disk from said driven disk, means cooperating with said drill for yieldably maintaining said member in disengaged relation, and a rock arm fixed to said bearing member and operable to move said rock shaft to interengage said driver and driven members and effect operation of said mandrel.

6. A honing machine comprising a stationary support, a horizontally disposed mandrel journaled in said support and provided with a longitudinally disposed groove and a plurality of longitudinally disposed ribs spaced peripherally from said groove, a shoe arranged in said groove and extending radially therefrom, an abrasive stick carried by said shoe, adjusting means in said mandrel and cooperatively engaging said shoe for adjusting 130

- the latter radially, said abrasive stick forming an abrasive cylinder engaging element and said ribs forming non-abrasive cylinder engaging elements, thereby causing the article 5 operated upon to be held in proper alignment with the tool, a horizontally disposed rock shaft journaled in said support in spaced relation with said mandrel, an electric drill mounted on one end of said rock shaft, a bearing member carried by said rock shaft, a friction driver wheel journaled in said bearing and adapted to be operatively associated with said drill, a friction driven wheel in non-rotative relation with said mandrel, and a 10 rock arm fixed to said bearing member and operable to rock said shaft and move said drill and said bearing member to interengage said disks.
7. In a hole grinding machine, an elongated mandrel adapted for rotation in the hole to be ground, said mandrel having a longitudinally disposed recess, an abrading element adjustably mounted in said recess, and a pair of longitudinally disposed guide elements formed integral with and projecting from the periphery of the mandrel in spaced relation with the abrading element and with each other.
8. In a hole grinding machine, an elongated mandrel adapted for rotation in the hole to be ground, said mandrel having a longitudinally disposed recess, an abrading element adjustably mounted in said recess, and a pair of longitudinally disposed guide elements formed integral with and projecting from the periphery of the mandrel, said guide elements being in spaced relation and non-uniformly spaced from the abrading element.
9. In a hole grinding machine, a grinding 40 tool comprising an elongated holder, an abrading element projecting radially from the holder and extending longitudinally thereof, means for varying the extent of projection of the abrading element beyond the periphery of the holder, and two spaced guide elements projecting in fixed position from the periphery of the holder and extending longitudinally thereof, the abrading element and the guide elements forming bearings for the work.
10. In a hole grinding machine, an elongated mandrel adapted for rotation in the hole to be ground, said mandrel having a longitudinally disposed recess, an abrading element 45 adjustably mounted in said recess, and a pair of longitudinally disposed guide elements formed integral with and projecting from the periphery of the mandrel, the guide element following the abrasive element with respect to the direction of rotation being closer to the abrasive element than the leading guide element.
11. In a hole grinding machine, a grinding tool comprising an elongated holder, an abrading element projecting radially from 50 the holder and extending longitudinally thereof, means for varying the extent of projection of the abrading element beyond the periphery of the holder without varying its position longitudinally of the holder, and two spaced guide elements projecting in fixed position from the periphery of the holder and extending longitudinally thereof substantially coextensive with the abrading element, said guide elements being relatively non-abrasive to the wall of the hole being ground.
12. In a hole grinding machine, a grinding tool comprising an elongated holder, an abrading element projecting radially from the holder and extending longitudinally thereof, means for varying the extent of projection of the abrading element beyond the periphery of the holder, and two spaced guide elements projecting from the periphery of the holder and extending longitudinally thereof coextensive with the abrading element, said guide elements being non-adjustably fixed to the holder.
13. In a hole grinding machine, a grinding tool comprising an elongated holder, an abrading element projecting radially from the holder and extending longitudinally thereof, means for varying the extent of projection of the abrading element beyond the periphery of the holder, and two spaced guide elements projecting from the periphery of the holder and extending longitudinally thereof coextensive with the abrading element, said guide elements being non-abrasive to the wall of the hole being ground, the abrading element and the guide elements forming bearings for the work.
14. In a hole grinding machine, a grinding tool comprising a mandrel adapted to contact with the wall of the hole along but three radially spaced surfaces of comparatively narrow breadth, one of said surfaces being an abrading surface and the other two non-abrading surfaces the abrading surface and the non-abrading surfaces forming bearings for the work, and means for varying the position of one of said surfaces with respect to the rotation axis of the mandrel to adjust the mandrel to different sizes of holes.
15. In a hole grinding machine, a grinding tool comprising a mandrel adapted to contact with the wall of the hole along but three radially spaced surfaces of comparatively narrow breadth, one of said surfaces being an abrading surface and the other two non-abrading surfaces the abrading surface and the non-abrading surfaces forming bearings for the work, and means for varying the position of the abrading surface with respect to the rotation axis of the mandrel to adjust the same to different sizes of holes.
16. In a hole grinding machine, a grinding tool comprising a mandrel adapted to contact with the wall of the hole along three radially spaced surfaces of comparatively nar-

row breadth, one of said surfaces being an abrading surface and the other two non-abrading surfaces the abrading surface and the non-abrading surfaces forming bearings for the work, and means for varying the position of one of said surfaces with respect to the rotation axis of the mandrel while the positions of the other surfaces remain fixed to adjust the mandrel to different sizes of holes.

17. In a hole grinding machine, a grinding tool comprising a bar, adapted for rotation in the hole to be ground, an abrading element projecting from the periphery of the bar and extending longitudinally thereof, means for varying the position of the abrading element with respect to the rotation axis of the bar, and a pair of ribs projecting in spaced relation from the bar and spaced from the abrading element, said ribs cooperating to hold the abrading element on a circular orbit during the rotation of the bar in a hole.

18. In a hole grinding machine, an elongated mandrel adapted for rotation in the hole to be ground, said mandrel having a longitudinally disposed recess, an abrading element adjustably mounted in said recess, and a pair of guide elements projecting from the periphery of the mandrel in spaced relation, said guide elements being composed of material adapted to wear by attrition as the mandrel is rotated in the hole being ground.

19. In a hole grinding machine, an elongated mandrel adapted for rotation in the hole to be ground, said mandrel being formed of an alloy of zinc containing copper and aluminum and having a longitudinally disposed recess, an abrading element adjustably mounted in said recess, and a pair of guide elements projecting from the periphery of the mandrel in spaced relation and formed integral therewith, said guide elements being adapted to wear by attrition as the mandrel is rotated in the hole being ground.

In testimony whereof I hereunto affix my signature this 23rd day of October, 1931.

JOSEPH SUNNEN.
